EXPANSION JOINT

Joseph William Heltzel, Warren, Ohio

Application April 10, 1935, Serial No. 15,713

2 Claims. (Cl. 94—18)

The present invention relates to expansion joints for use in roadways of concrete and the like, and more particularly to certain improvements in the members of the joint and certain additions thereto.

An object of this invention is to provide an expansion joint which will more effectively transmit load pressure between adjacent slabs in the roadway.

Another object of the invention is to provide a pair of relatively movable expansion joint members with combined anchoring and guiding means for solidly holding the joint members to their respective slabs and for maintaining the members in proper alignment under load pressure and for relative movement as the joint expands and contracts.

A further object is to provide a joint of this character having expansion joint members which are equal substantially to the depth of the road slabs to insure a solid joint and the maintenance of adjacent slabs at the same level, particularly under load carrying conditions.

Another object is to provide the expansion joint members with combined anchoring and guide bars so proportioned and mounted in the joint as to offset breaking of the slabs transversely across the road along the lines of the ends of the anchors.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a top plan view of an expansion joint ready for insertion in a roadway, and showing the opposite side road sections connected together at the middle portion of the structure.

Figure 2 is an enlarged transverse section taken through the same substantially on the line 2—2 of Figure 1, showing the adjacent road slabs molded about the joint.

Figure 3 is a similar view taken on the line 3—3 of Figure 1.

Figure 4 is a horizontal section taken longitudinally through the interfitting ends of the joint sections at the middle of the road.

Figure 5 is a horizontal section taken through the outer end of one of the joint sections, showing the closure plate at the end of the joint, and

Figure 6 is an enlarged transverse section similar to Figure 2, but showing a slight modification in the use of a sleeve for the sliding end of the anchor rod.

Referring now to the drawing, the expansion joint comprises an inner channel member 20 which has its cavity facing outwardly away from

the joint to receive therein the adjacent portion of the road slab 21 to hold the inner channel member 20 rigidly on the slab 21 and for movement therewith during the expansion and contraction of the slab. Slidably supported on and enclosing the inner channel member 20 is an outer channel member 22 which is of similar construction and which is proportioned slightly greater than the inner channel member so as to freely and slidably receive the same. The channel member 22 is molded into the opposite slab 23 of the roadway and is adapted to move therewith during the expansion and contraction of the slab 23. The channel members 20 and 22 are disposed in a vertical edgewise position in the road joint as shown in Figure 2 and the lower flange of the outer channel member 22 may be flush with and rest upon the surface of the sub-grade 24 of the roadway so as to support both of the channel members 20 and 22 in their vertical edgewise positions, and the widths of the channel members are sufficient to approach the upper surface portions of the slabs 21 and 23.

The outer channel member 22 carries a cap strip 25 which may be of cork, soft rubber or premolded asphaltic material secured by a suitable adhesive substance to the upper flange of the outer member for holding the cap strip 25 in place during the molding and setting of the slabs 21 and 23.

The outer channel member 22 is provided at each end, as shown in Figure 5, with an end wall 26 which may be a portion of the channel member bent at right angles thereto in the direction of its flanges so as to overlap the opposite ends of the inner channel member 20 and thus effectively close the opposite ends of the space between the joint members. These joint members are constructed at their upper portions to conform substantially to the crown of the road and the lower portions of the joint members 20 and 22 are constructed to the configuration of the sub-grade 24. The outer channel member 22 is also provided along its outer side with a shear bar 27 which may be suitably formed thereon or welded thereto and which is adapted for embedding in the adjacent road slab 23 to hold the outer channel member 22 against vertical displacement from its slab.

From Figures 1 and 4, it will be noted that a stepped or scarf joint is provided at the meeting inner ends of the expansion joint sections.

In the present instance the outer channel member 22 of one section is longer at its inner end than the inner channel member 20 and the opposite expansion joint section is oppositely disposed with its outer channel member 22 of less length than its inner channel member 20, the distance in lengths being equal on both sections so that the desired overlap may be provided. This

split and overlapping joint is shown at 28 in Figures 1 and 4, and is provided merely to produce an expansion joint in two parts which are easily handled as against a single expansion joint 5 structure of the full width of the road.

For the purpose of maintaining the relatively movable members 20 and 22 in alignment and also in assisting in the transfer of the load between the slabs 21 and 23 of the respective joint 10 members, combined anchoring and guide pins are employed. As shown in the present instance the inner channel member 20, Figure 3, is provided with a plurality of anchor pins 29 which are in the form of rods disposed transversely through 15 the member 20 and fixed thereto in any suitable manner, such as by welding 30. The anchor pins 29 are turned down at their outer ends as shown, or given any other suitable configuration to effect anchorage, and are adapted to be embedded 20 in the adjacent road slab 21.

The pins 29 are of any suitable number spaced lengthwise throughout the inner channel member 20 and serve to hold the inner channel member 20 on the end of its slab 21. Each anchor pin 29 25 extends through the member 20 and extends slidably through the opposite channel member 22 and slidably into the opposite slab 23 thus, the slab 23 with its outer channel member 22, may move toward and from the slab 21 with its channel member 20. The end of the anchor pin 29 which projects across the joint provides a guide pin 31 which may have a coating of heavy paint thereon, as shown in Figure 3, to insure the free sliding of the pin 31 in the slab 23. The outer 30 channel member 22 is provided, for each pin 31, with a bushing or bearing collar or boss 32 to take up wear about the opening through the channel member 22 and also to provide a substantial surface bearing upon the pin 31. This 35 structure maintains the channel members 20 and 22 in substantially parallel relation throughout their movements toward and from each other.

As shown in Figure 2, the outer channel member 22 is provided with anchor pins 33 which are 40 given any suitable configuration to effect anchorage in the slab 23 and which project through the two channel members, 22 and 20, and are fixed to the outer channel member 22 by welding 30 as above described.

The inner channel member 20 is provided with 45 openings therethrough and bosses or bearing rings 32 similar to the structure above described but in line with the anchor pins 33, and the latter are provided with extensions forming guide and 50 alining pins 34 which slidably engage through the channel member 20 and its slab 21. The pins 34, like the pins 31, may be provided with a heavy coating of paint or the like to insure sliding movement of the pins in the slab. The 55 anchor pins 33 with their guide pins 34 are disposed in any suitable order with respect to the anchor pins 29 and their guide pins 31.

In Figure 1, it will be noted that the outer channel member 22 is provided with twice as many 60 anchor pins 33 as the inner channel member 20. This is to insure the firm mounting of the outer channel member on its slab 23 and also on account of the flanges of the inner channel member 20 affording additional support for the inner channel member on the slab 21, a lesser number 65 of anchors 29 being required.

As shown in Figure 6, instead of coating the

guide pins 31 and 34 with paint, slide tubes 35 5 may be embedded in the slabs for the respective guide pins, such as 34, and the guide tubes 35 may be welded or otherwise suitably secured to the adjacent channel member to substantially form a part thereof and admit of the free movement of the guide pins through the channel member and the tube 35.

From Figure 1, it will be noted that the guide pins 31 and 34 are of less length than are the 10 anchors 29 and 33, so that at each side of the joint there is an uneven bracing or reinforcement in the slabs 21 and 23 to prevent possible breakage or cracking of the slabs along any definite transverse line. 15

In installing the joint in a roadway, the channel members 20 and 22 may be supported in upright position by engagement of stakes or the like with the anchor pins 29 and 33 so as to hold the joint in position until the concrete or other 20 material of the road is poured in against the opposite sides of the joint.

What is claimed is:—

1. An expansion joint, comprising a pair of telescopic channel members nested one within the other for slidable interrelation and with the outer member larger than the inner member and with the flanges of both members extending in the same direction, a cap strip mounted on the upper flange of the outer member, said outer member having a shear bar at its outer side for embedding in a road slab molded against the outer side of the outer member to hold the latter from vertical displacement relatively to the slab, a plurality of anchor pins fixed to the outer member 30 and extending outwardly therefrom to hold the member to the road slab and extending inwardly therefrom for slidable engagement through the inner member and in the opposite slab thereof, said inner member having bearing openings 40 therethrough for receiving the inner extensions of the anchor pins to maintain the members in alignment, a second plurality of anchor pins fixed to the inner channel member and extending outwardly therefrom to hold the inner member to an adjacent road slab molded against the outer side of the inner member and having inner ends 45 extending slidably through the outer channel member and its slab, said outer channel member having bearing openings therethrough to receive the inner ends of the anchor pins of the inner member to maintain the members in alignment, said anchor pins extending irregular distances from the opposite sides of the channel members to prevent straight transverse lines of cracking 50 in the molded road slabs.

2. In an expansion joint, a pair of interfitting relatively slidable channel members, a plurality of transversely disposed anchor pins extending through both of the members with some of the 60 pins secured to one channel member and having long ends extending to one side of said channel member and having short ends slidably engaging through the opposite channel member, and with the other pins secured to the opposite channel 65 member and having long ends extending from the opposite side of the channel members and short ends slidable through said first channel member, whereby the ends of the anchor pins project irregular distances from the opposite sides of the 70 channel members.

JOSEPH WILLIAM HELTZEL.
